US00D657583S

(12) **United States Design Patent**
Wilson et al.

(10) **Patent No.:** US D657,583 S
(45) **Date of Patent:** ** Apr. 17, 2012

(54) **CHAIR**

(75) Inventors: **Scott Wilson**, Chicago, IL (US); **D. Matthew Puhalla**, Chicago, IL (US)

(73) Assignee: **Steelcase Inc.**, Grand Rapids, MI (US)

(**) Term: **14 Years**

(21) Appl. No.: **29/402,543**

(22) Filed: **Sep. 23, 2011**

Related U.S. Application Data

(62) Division of application No. 29/360,949, filed on May 3, 2010, now Pat. No. Des. 648,553.

(51) **LOC (9) Cl.** **06-01**

(52) **U.S. Cl.** **D6/366; D6/500**

(58) **Field of Classification Search** D6/334–336, D6/360–369, 373–374, 379–380, 498, 500–502, D6/601; 297/284.4–284.5, 291, 297, 411.2, 297/411.27–411.29, 452.13, 452.19, 452.21, 297/452.29, 452.3, 452.56, 452.64

CLAIM

We claim the ornamental design for the chair, as shown and described.

DESCRIPTION

FIG. 1 is a perspective view of the chair embodying the present invention;

FIG. 2 is a front perspective view of the chair shown in FIG. 1;

FIG. 3 is a side elevational view of the chair shown in FIG. 1, the opposite side view being a mirror image thereof;

FIG. 4 is a rear perspective view of the chair shown in FIG. 1;

FIG. 5 is a top plan view of the chair shown in FIG. 1; and,

FIG. 6 is a bottom plan view of the chair shown in FIG. 1.

1 Claim, 5 Drawing Sheets
